Specification of Letters Patent.

Patented Dec. 2, 1913.

Application filed August 18, 1911. Serial No. 644,723.

To all whom it may concern:

Be it known that I, CHARLES H. VOGEL, a British subject, residing in Vancouver, in the county of Vancouver, Province of British Columbia, Dominion of Canada, have invented certain new and useful Improvements in Type-Writing Machines, of which the following is a specification.

The present invention relates to mechanism operated by pneumatic or like power, for driving in letter-feed direction, and for returning, the carriage of a typewriter, and for operating the line spacer thereof; all under the control of suitable keys.

More particularly the invention relates to a construction and arrangement of the control key connections, whereby a number of different operations may be performed, depending upon the manner in which the keys are operated, to wit: a construction and arrangement of key-controlled connections, for returning the carriage at any desired speed, and for varying the speed of return from line to line without special setting of the apparatus: for returning the carriage at a predetermined and uniform speed upon a certain operation of the key connections (as where the return is made from a full line), and for varying the speed according to the length of the line or for other reasons, by a special operation of the key connections at other times; for setting the key connections so as to cause the line spacer to operate whenever the carriage is re-

turned; for setting the key connections so that the carriage return and line-spacing operations may be effected independently, that is to say, so that the carriage may be returned without line-spacing, and so that the line-spacer may be operated once or any number of times without movement of the carriage; for operating the key connections, so that, even in event the same are set to permit of independent operation of the

carriage return and line spacing mechanisms, the two mechanisms may nevertheless be operated together, when desired, without changing the setting: for arresting the carriage at any point of its return by the operation of a key which instantly applies a brake or other stop device, and which may be the key by means of which the return movement was initiated: the control key connections having preferably a normal setting such that a letter-feed pneumatic drive

of the carriage, for writing the lines, is effected whenever a type key is operated; and the connections being automatically returned to such normal setting after each carriage return or line spacing movement. 60

Other features of the invention will hereinafter appear by reference to the accompanying drawings in which:

Figure 1 is a top plan view of an Underwood typewriter in which the present invention is incorporated. Fig. 2 is a view in rear elevation, of the machine shown in Fig. 1, certain parts being broken away or in cross section for better illustration of the apparatus. Fig. 3 is a right hand end view 70 of the machine, a few of the parts being broken away, or in cross section, to show the apparatus more clearly. Fig. 4 is a cross section through the slide-valve chest and cylinder casting near the same, and showing also the several air connections for controlling the mechanisms. Fig. 5 is a cross section of the 3-way valve shown in Fig. 4, the valve being differently set in the two figures. Fig. 6 is a perspective view 75 showing the mechanical key controlled connections for cutting off the air for a slow carriage return, and for applying the brake to stop the carriage. Fig. 7 shows the key of Fig. 6 when that key is thrown to apply the brake. 80

The typewriter, to which the invention is shown as applied, is an Underwood typewriter. The main frame of the typewriter is shown at 1, and the carriage frame at 2. The rod 3 of the main frame, at the rear of the carriage, serves as attachment and guide for the carriage on the main frame. The carriage is drawn forward in letter-feeding direction by a spring not shown and is controlled by the usual escapement pinion 4 and escapement rack 5, the latter being carried by arms 6 pivoted to the carriage at either end of the machine, so that by rocking the arms the rack may be lifted from the pinion 4 to release the carriage when desired. The release key 7 is integral with one of the arms 6, and when depressed causes the rack to be lifted. The letter feed action of the escapement is effected from the type bars 8 in the usual manner by means of a universal bar 9 which, by heels 8^a on the type bar, vibrates dogs 9^a alternately into engagement with the escapement wheel 10 so that pinion 4 feeds forward the 85

100

105

110

rack at each key stroke. The type keys 11 are carried by key levers 12 pivoted to the main frame at 13, and the movement of levers 12 is transmitted to the type bars by 5 means of bell crank levers 14 pivoted at 15.

The platen 16 is carried by the shaft 17 which has bearing at either end in the carriage frame 2. A hand wheel 18 is shown at either end of the shaft 17, and on the left 10 hand end of the shaft, looking from the front of the machine, is the line spacing ratchet wheel 19. The wheel 19 is actuated by pawl 20 carried by the slide 21, which in turn is operated by the line spacing lever 22, 15 the latter being a bell crank lever pivoted at 23 to the carriage frame. Coil spring 24, secured at one end to the slide 21 and at its other end to the frame, acts to hold the slide against the arm 25 of the lever 22, and 20 to return the slide and pawl after each operation of the line spacing wheel. The line spacing lever may, as heretofore, be operated by finger piece 26, but in the present machine is adapted to be power-operated by 25 pneumatic pressure from an air cylinder 27 to which air is admitted by way of a connection 28^a (see Figs. 1 and 3) under control of certain keys at the keyboard as later to be explained. Within the cylinder 27 is a 30 piston 28 having a stem 29 which projects forward to the line spacing lever and is adapted to bear against an arm 30 fast to the line spacing lever. When, therefore, the piston 28 moves forward, it operates the 35 line spacing lever 22, and with it, the slide 21 and the line spacing wheel 19, precisely as if these parts were operated from the finger piece 26. The spring 24, acting on the slide 21, holds the lever arm 30 against 40 the piston stem 29. After the line spacing operation the supply of air through the tube 28^a is cut off, and a coil spring 31 within the cylinder 27 returns the piston to normal position. The cylinder 27 is fast to and is 45 carried by the carriage, and the connection 28^a is a flexible connection of sufficient length to permit of the movement of the cylinder with the carriage.

As heretofore explained, one of the objects 50 of the present invention is to effect a power return of the carriage, at will, accompanied or not, by a line spacing of the platen. The line spacing operation has been in part described and will be further explained in connection with the carriage return mechanism. The carriage return, and the letter feed drive, are both effected, in the form of the invention herein described, by a compressed air engine.

60 The cylinder 35 of the air engine is suitably supported by brackets 36^a from the main frame 1 of the machine, at the rear thereof. Fig. 2 which is a rear view of the machine shows the piston 36 within the cylinder 35, the stem 37 of the piston passing

70 through one of the heads 38 of the cylinder and being extended a considerable distance to the left. At or near the outer end of the piston stem, there is secured to it an arm or tie 39 by means of which it is made fast to one of the tie rods 40 of the carriage. It follows that with the connections as shown, the carriage must always move with the piston, and in the same direction and to the same degree as the latter. This, however, is not an essential feature of my invention. 75

Each of the heads 38 of the cylinder is provided with an inlet port 42, and with an exhaust port 43. Flexible connections 44 and 45 respectively lead from these ports to corresponding passages 46 and 47 which lead through the walls of the cylinder casing to the valve chest 48. The valve chest is connected by means of a tube 50 with the compressed air tank 51, and is provided with a suitable exhaust outlet 52, and with an ordinary slide valve 53 to control the inlet and exhaust of air for both ends of the cylinder. The valve, when in the position shown in Fig. 2, is set for the letter-feed drive of the carriage, and so permits passage of compressed air from the tank 51 through the chest 48, thence (in Fig. 2) through the left hand inlet passage 47, tube 44, and port 42 so that when a type key is depressed to operate the escapement mechanism, the pressure of air from the left hand port 42 causes the piston to advance a step with the carriage until the latter is arrested again by the escapement mechanism. As the piston advances from left to right, the air in front of it exhausts through the right hand exhaust port 43, to the tube 45 which connects therewith, thence escaping by passage 46, to the passage 54 across the inner face of the slide valve and so to the exhaust port 52. The inlet ports 42 are shown as controlled by check valves 55 so that air forced out of the piston must always be by way of the proper exhaust port. The exhaust port may be regulated as to its capacity by means of a set valve 56, and the movement of the piston thus 100 steadied or controlled. 105

When the end of a line is reached, or whenever it is desired to return the carriage, the slide valve 53 is moved to the left in Fig. 2 to close the left hand inlet and open the left hand exhaust, and to open the right hand inlet and close the right hand exhaust. This movement of the slide valve is effected by means of a stem 57, the outer end of which is secured to one arm of a bell crank lever 58, pivoted at 59 to a lug 60 on the lower face of the cylinder 35. To the other arm of bell crank lever 58 is attached the upper end of a link 61, the lower end of which link is secured to a lever 62 fast on a rock shaft 63. The rock shaft 63 has a 115 120 125 130

bearing in a bracket 64 at the rear of the machine, and extends forward (see Figs. 1 and 3) to a bearing 65 in the main frame near the key board. It carries on its forward end an arm 66 which in effect forms with the arm 62 a two-armed lever pivoted at 63. Positioned along, and adjacent to, the lever arm 66 are three keys A, B and C, carried on stems or plungers 67, 68, and 69 respectively. The key stems 67, and 69 are each provided with a tooth or pin 70, and 71, respectively, which extend over the lever arm 66, whereby when either key A or key C is depressed the pin carried by the stem thereof strikes the arm 66, rocks the shaft 63 and raises the arm 62 with the link 61 to rock the bell crank 58, thus throwing the slide valve to the left of its Fig. 2 position. A coil spring 72 secured at one end to the lever arm 62 and at its other end to the machine frame, holds the link 61 normally depressed; and the normal position of the slide valve is therefore the position in which it is shown in Fig. 2, that is to say, the position in which it is set for letter-feed or writing. After each operation of either key A or C the spring 72 returns the slide valve to this normal position.

When the slide valve is thrown from normal position, whether by key A or key C, the air from the tank 51 enters the right hand inlet passage 47, tube 44, and inlet port 42 at that end of the cylinder, thus causing the piston to be driven in carriage return direction. During this movement the air in front of the piston is exhausted through the left hand port 43, tube 45 and passage 46 to the valve passage 54 and the exhaust 52.

It is desirable, particularly, where the drive is a long one, as in the return movement of the carriage, that provision be made at the end of the stroke for cushioning the parts against the shock which would otherwise occur, due to the momentum of the carriage. In the present invention an air cushion is formed for the piston as the latter approaches the end of its stroke so that the piston and cylinder form in effect a dash pot for gently arresting the carriage. On each side of the piston is a boss 75, adapted to fit closely within a counter-bore 76 in the opposing cylinder head. It will be noted that the exhaust ports 43 lead from the counter-bores 76. Therefore when the piston approaches the end of its stroke and the boss enters the counter-bore, the exhaust port is closed, and the air which remains between the piston and the cylinder head is held and compressed to form a cushion. By regulating the position of the set valve 56, the exhaust can be controlled throughout the entire stroke of the piston thus governing the movement of the carriage at all times.

Key C is the key normally used for throwing the slide valve 53 to return the carriage. When, however, it is desired to return the carriage at a slower speed than the normal, then key A is the key used. Key A in addition to operating the levers 66 and 62 to throw the slide valve 53 as heretofore described, has also certain other functions. One of the functions of key A is to choke or close to a greater or less degree, the right hand (Fig. 2) inlet port 47 so that the amount of air entering the cylinder by way of this port may be made less than the capacity of the port, whereby there results a slower return drive of the carriage. This partial choking or closing of the right hand inlet port 47 is effected by means of a valve 78 in the form of a rod or plunger, the end of which is adapted to be forced into the port passage 47. The upper end of this valve rod has bearing in the cylinder casting, and its lower end connects with one arm of a bell crank lever 79 pivoted at 80 on a bracket 81 fast to the main frame of the machine. The lower arm of the bell crank 79 is connected by a link 82, which (see Figs. 6 and 3) extends from the rear of the machine forward and connects near the front of the machine to an arm 83 which is fast on a rock shaft 84. The rock shaft 84 extends likewise with the machine parallel to the front thereof and has bearing at suitable points in the main frame. At or near the left hand end of the shaft 84 (looking from the rear), there is fast to this shaft 100 an arm 85 which extends forward to the key A and carries on its end a tooth or pin 86 which crosses in front of the stem 69 of the key A.

Carried by the stem 69 of key A is a cam 105 or wedge 87, which, when the key is depressed, engages and depresses the pin 86 on the lever arm 85, thereby rocking the shaft 85 and drawing forward the link 82. The link 82 being pulled forward rocks the bell crank 49 and raises the valve rod 78 to choke the port passage 47. The more the key A is depressed the greater will be the movement of the valve rod 78, due to the increasing thickness of the cam or wedge. 110 Consequently, according to the amount of depression of key A the speed of the carriage return may be varied at will. A coil spring 88 bearing against a collar 89 on the valve rod 78 tends to depress the latter and 115 serves to return the key operated connections thereof to normal position when the key A is released. By means of a turn buckle 90 in the valve rod 78, the length of the latter may be adjusted according to the 120 restriction desired in the passage 47.

The key A has still another function, to wit: that of applying a brake to the carriage whenever during the return throw of the carriage it is desired to arrest the latter. 130

In Fig. 1 there is shown secured to the carriage frame by bracket arms 91 a so-called brake rod 92 against which a brake shoe 93 is adapted to be pressed upon proper operation of the key A. The brake shoe 93 (see Figs. 3 and 6) is pivoted at 94 to a lug on the cylinder casting 35 and has an arm 100 which extends downward and forward under the cylinder. The forward end of the shoe arm 100 connects with a link 101, the lower end of which is attached to a bell crank 102 pivoted at 103 to a bracket 104 on the lower rear face of the main frame 1. The lower arm of the bell crank 102 is connected by a link 105 which extends to the left (see Fig. 2) parallel to the rear of the typewriter, and at its left hand end connects with an arm 106 fast to a rock shaft 107. The rock shaft 107 extends from the rear to the front of the machine and has bearings in suitable brackets 108 and 109. At its forward end, there is fast to the shaft 107 a lever arm 110 at the lower end of which is carried a pin 111 adjacent to the key stem 69 and to the right thereof looking from the front of the machine. The key stem 69 in addition to having up and down movement in the frame members 112 and 113, is adapted to be swung or rocked laterally, as by means of a finger piece 115, in such manner as to bring the key stem into contact with the pin 111 on the lever arm 110 (see Fig. 7). This lateral movement of the key A therefore causes the lever 110, with rock shaft 107 and lever 106, to be turned in such wise as to draw upon the link 105, rock the bell crank 102, draw down the link 101, and rock the brake lever, thereby pressing the brake shoe against the brake rod 92, and so stopping the carriage. To permit of the lateral movement of the key A, the keyboard 113 is slotted at 116, and stem hole in the plate 112 is of a shape indicated at 112^a. A spring 117, attached at one end to the frame and at the other end to the lever 110, returns the brake shoe connections to normal position when the key A is released. A coil spring 69^a serves to return key A to normal position after each operation thereof, and in view of the size and shape of the hole 112^a, a washer 133 which loosely fits the key stem is preferably used as a bearing for spring 69^a. A pin 134 by engagement with the plate 112 limits the upward throw of the key by the spring 69^a. A similar spring 67^a returns key C to normal position and a similar pin 135 determines the normal position of key C.

It has been noted that the line spacing wheel is operable by means of a pneumatic connection 28^a which leads to the cylinder 27 on the carriage. It has also been stated that the platen may be line-spaced from the

connection 28 conjointly with the return of 65 the carriage, or independently thereof. The carriage return is effected either at high speed by key C or at a lower speed by key A, and either of these keys when operated to return the carriage may be made to line 70 space the platen. To this end, there is provided a branch air passage 118 from the right hand inlet passage 47 (see Figs. 1 and 4) to a three way valve 119, to which valve the pipe 28^a from the line spacing cylinder 75 27 also connects, so that when valve 119 is set as shown in Fig. 4, there is an open passage from the compressed air tank 51 by way of the valve chest 48, the passages 47 and 118, through three way valve 119 and 80 pipe 28^a, to the line spacing cylinder 27. The movement of the slide valve to Fig. 4 position will therefore cause not only the return of the carriage but also the line spacing of the platen when valve 119 is set as in 85 Fig. 4.

When it is desired to set the machine for line-spacing independently of the carriage return, the three way valve 119 is moved by means of its key 120 from Fig. 4 to Fig. 5 90 position, thereby cutting off the tube 28^a from the valve chest by way of the pipe 118, and opening a passage from the tube 28^a to a tube 121 which also connects with valve 119. The tube 121 leads from valve 119 to 95 the valve chest 48, and through the latter connects with the compressed air tank 51, but it has in it a valve 122, which, (see in Figs. 2 and 4), is located at or near the key B, and is operable from the key B by means 100 of an arm or key 123 and a hook 124. The position of the valve 122 when the key B is in normal elevated position is such as to cut off the compressed air from the tube 28^a. When however the key B is depressed, its 105 stem 68 by means of the hook 124 and valve key 123 throws the valve 122 into such position as to open the connection between the compressed air tank and the tube 28^a by way 110 of the slide valve chest 48. A line spacing operation is therefore effected every time the key B is operated regardless of whether or not the carriage is returned, provided only that the three way valve 120 is set as in Fig. 5. Spring 136 returns key B and valve 122 115 to normal Fig. 4 position after each operation thereof. When the valve 119 is set as in Fig. 5, and it is desired to both line space and return the carriage, then key B is depressed together with whichever of the keys 120 A or C is used for the carriage return.

For the purpose of adjusting the stroke of the piston 36 and of determining the marginal stopping positions of the carriage, the heads 38 are adjustable in the cylinder 35. 125 As shown in Fig. 2 each cylinder head is provided with a rack 125 which lies parallel to the direction of movement of the piston

and meshes with a pinion 126 on a shaft 127 which is suitably supported in the cylinder casing. Also fast to the shaft 127 is a disk 128 having a circle of pin holes 129 spaced 5 one from the other. According to the angular position of the disk 128, one or the other of the pin holes 129 may be brought into registration with a corresponding pin hole 130 in the casting 35, and when in such registration a pin 131 may be passed through the registering holes to hold the disk 128, and consequently the rack and cylinder head, in the adjustment selected. The shaft 127 may be provided with a hand wheel 132 for moving the cylinder head to adjusted position.

A résumé of the operation of the machine is as follows: Assuming that the character of the work is to be such that the platen is to be line-spaced on each return of the carriage; then before the writing is commenced the valve 119 is set as shown in Fig. 4 and the connections from the tank 51 to the line spacing cylinder 27 will thereafter be under the control of the slide valve 53, and consequently of the keys A and C. The normal position of the slide valve 53 being its Fig. 2 position, an open connection is normally maintained from tank 51 to the left hand end of the cylinder 35, and a pressure is 20 therefore maintained on the piston 36 for driving the carriage step by step in letter feed direction as the type keys release the carriage from the escapement mechanism.

The drive in letter feed direction may be a 35 long drive, as in tabulating machines, provided the escapement rack be held out of engagement with the escapement wheel. When, however, the end of the line is reached or whenever the carriage is to be 40 returned, key C is operated, that is, if the return is to be at the normal high speed; otherwise key A is operated. Whichever of these keys is operated, the slide valve 53 is thrown to Fig. 4 position and the air pressure is applied to piston 36 from the other 45 side. Simultaneously air by way of pass 118, valve 119 and tube 28^a actuates the line spacer. If key A is the key operated for return, then in addition to, and just before 50 the valve 53 is thrown, the valve rod 78 is lifted a greater or less distance (according to the amount of depression of key A) to restrict the pass 47 more or less, thus cutting down the amount of air entering the cylinder 35, until the return is as slow as may be 55 desired. If during the carriage return, it is desired to stop the carriage entirely, the key A is rocked laterally to Fig. 7 position to apply the brake shoe 93. So long as key A 60 or key C is held depressed, and unless the brake is applied, the carriage will move to the left until the piston 36 is stopped by the head 38, which as stated may be set for any desired margin. Assuming now that the

character of the work is such as to make it 65 desirable to have independent operation of the carriage return and line spacing mechanisms at certain times, then the valve 119 is set as shown in Fig. 5. The line spacer can now be connected with the tank 51 only by 70 way of valve 122 under control of key B. Whenever key B is operated the line spacer operates regardless of whether there is a carriage movement or not, and regardless of 75 in which direction the carriage may be moving. The line spacing and carriage return movement may however be made together, although the valve 119 be set as in Fig. 5, by operating either key A or key C with key B.

It will be noted that the tube 50 and its 80 extension in the passage 47 may be considered a main line of fluid supply, while the passage 118 and its extension tube 28^a constitute a branch for operating a line-space mechanism. The tube 121, which is controlled by key B through valve 122, may then be regarded as a shunt passage.

The invention has been shown in connection with an Underwood typewriter, but it will be obvious that it is adaptable to various other typewriters.

It is also evident that the construction and arrangement of the parts may be variously and considerably altered within the scope of the invention.

Having thus described my invention, I claim:

1. In a typewriting machine, a carriage, a line spacing mechanism, a source of power and connections therefrom for driving the carriage and operating the line spacing mechanism, means for setting said connections to cause the line spacing mechanism to operate when the carriage is driven and means for setting said connections to permit the line spacing mechanism to be operated independently of the drive of the carriage.

2. In a typewriting machine, a carriage, a line spacing mechanism, a source of power and connections therefrom for driving the carriage and operating the line spacing mechanism, means for setting said connections to drive the carriage at different speeds and for causing the line spacing mechanism to be operated upon drive of the carriage at either speed, and means for setting said connections to permit the line spacing mechanism to be operated independently of the drive of the carriage.

3. In a typewriting machine, a carriage, a source of power and connections therefrom for driving the carriage, means for setting said connections to effect the carriage drive, and means operable at any time during the carriage drive to arrest the carriage as soon as said means is operated.

4. In a typewriting machine, a carriage, a source of power and connections there-

from for driving the carriage, means for setting said connections to effect the carriage drive, and a brake for arresting the carriage at any time during the drive of the same.

5. In a typewriting machine, a carriage, a source of power and connections therefrom for driving the carriage, means for setting said connections to effect the carriage drive, means operable at any time during the carriage drive to arrest the carriage as soon as said means is operated, and a single key which controls both the setting of the driving connections and the operation of carriage arresting means.

10. 6. In a typewriting machine, a carriage, a line spacing mechanism, a source of power and connections therefrom for returning the carriage and operating the line spacing mechanism, means for setting said connections to cause the line spacing mechanism to operate when the carriage is returned and means for setting said connections to permit the line spacing mechanism to be operated independently of the return of the carriage.

20. 7. In a typewriting machine, a carriage, a line spacing mechanism, a source of power and connections therefrom for returning the carriage and operating the line spacing mechanism, means for setting said connections to return the carriage at different speeds and for causing the line spacing mechanism to be operated upon return of the carriage at either speed, and means for setting said connections to permit the line spacing mechanism to be operated independently of the return of the carriage.

30. 8. In a typewriting machine, a carriage, a source of power and connections therefrom for returning the carriage, means for setting said connections to effect the carriage return, means operable at any time during the carriage return to arrest the carriage as soon as said means is operated, and a single key which controls both the setting of the carriage driving connections and the operation of carriage arresting means.

40. 9. In a typewriting machine, a carriage, a line spacing mechanism, a source of fluid under pressure, a cylinder with a piston therein, said piston being connected to the carriage and said cylinder having a fluid connection to the source of the fluid, a valve controlling the fluid connection to the cylinder, a fluid connection for operating the line spacing mechanism, said last named connection being branched from said cylinder connection at a point between the cylinder and the aforesaid valve, and key controlled means for operating said valve to simultaneously return the carriage and operate the line spacer.

50. 10. In a typewriting machine, a carriage, a line spacing mechanism, a source of fluid under pressure, a cylinder with a piston therein, said piston being connected to the

carriage and said cylinder having a fluid connection to the source of the fluid, a valve controlling the fluid connection to the cylinder, a fluid connection for operating the line spacing mechanism, said last named connection being branched from said cylinder connection at a point between the cylinder and the aforesaid valve, one key controlled means for operating said valve, and another key controlled means for modifying the fluid capacity of said cylinder connection and for operating said valve, whereby according to which of said key controlled means is operated, the carriage may be returned at a greater or less speed and the line spacer simultaneously operated.

70. 11. In a typewriting machine, a carriage, a line spacing mechanism, a source of fluid under pressure, a cylinder with a piston therein, said piston being connected to the carriage and said cylinder having a fluid connection to the source of fluid, means for opening and closing said fluid connection and for regulating the volume of fluid admitted to the cylinder, whereby, according to the volume of fluid admitted, the carriage will be driven at a greater or less speed by the piston.

75. 12. In a typewriting machine, a carriage, a line spacing mechanism, a source of fluid under pressure, a cylinder with a piston therein, said piston being connected to the carriage and said cylinder having a fluid connection to the source of fluid, means for opening and closing said fluid connection and for regulating the volume of fluid admitted to the cylinder, whereby, according to the volume of fluid admitted, the carriage will be driven at a greater or less speed by the piston, said fluid admitting and regulating means comprising two keys, one of which is operated for high speed and the other for lower speed of carriage drive.

80. 13. In a typewriting machine, a carriage, means under the control of fluid pressure for driving said carriage, a pressure-varying device for effecting the operation of said carriage driving means, and key controlled means for regulating the variation of fluid pressure in said device whereby said carriage driving means may be operated at different speeds.

85. 14. In a typewriting machine, a carriage, a line spacing mechanism, a source of fluid under pressure, a cylinder with a piston therein, said piston being connected to the carriage and said cylinder having a fluid connection to the source of the fluid, a valve controlling the fluid connection to the cylinder, a fluid connection for operating the line spacing mechanism, said last named connection being branched from said cylinder connection at a point between the cylinder and the aforesaid valve, means for restricting said cylinder connection between

the cylinder and said valve, key controlled means for operating said valve alone, and other key controlled means for operating said restricting means together with said valve.

5 15. In a typewriting machine, a carriage, a source of fluid under pressure, a cylinder with a piston therein, said piston being connected to the carriage and said cylinder having a fluid connection to the source of fluid, a valve controlling said fluid connection, means between the valve and the cylinder for restricting said connection, key controlled means for operating said valve to admit fluid to the cylinder sufficient to return the carriage at considerable speed, and key controlled means for operating said restricting means as well as the valve, whereby the fluid admitted to the cylinder will be such as to return the carriage at a lesser speed.

10 16. In a typewriting machine, a carriage, a source of fluid under pressure, a cylinder with a piston therein, said piston being connected to the carriage and said cylinder having a fluid connection to the source of fluid, a valve controlling said fluid connection, means between the valve and the cylinder for restricting said connection, key controlled means for operating said valve to admit fluid to the cylinder sufficient to return the carriage at considerable speed, and key controlled means for operating said restricting means as well as the valve whereby the fluid admitted to the cylinder will be such as to return the carriage at a lesser speed, and a brake operable to arrest the carriage at any desired point on the return of the same.

15 17. In a typewriting machine, a carriage, a carriage return mechanism operable by fluid pressure, a line spacing mechanism, an actuator for the line spacing mechanism also operable by fluid pressure, and means whereby the carriage return and line spacing mechanisms may be operated together or singly.

20 18. In a typewriting machine, a carriage, a carriage return mechanism operable by fluid pressure, a line spacing mechanism, an actuator for the line spacing mechanism also operable by fluid pressure, and means for setting the fluid connections whereby the carriage return and line spacing mechanisms may be operated together or singly.

25 19. In a typewriting machine, a carriage, a carriage return device having a connection to a source of fluid under pressure, a line spacing mechanism, an actuator for said line spacing mechanism having a connection branched from said first named fluid connection, a valve in said first named connection between the source of pressure and the branch to the line spacer, key controlled means for operating said valve whereby the

carriage return and line spacing mechanisms may be operated together, a shunt connection from a point of said first connection between said valve and the source of fluid to a point of said branch to the line spacer beyond said valve, a second valve at the juncture of said shunt and said line spacer branch whereby said branch may be closed either to the shunt or to the fluid supply except by way of the shunt, according to the setting of said second valve, and key controlled means for opening and closing the passage through the shunt so that when the second valve is set for operation of the line spacer by way of the shunt, said key controlled means determines that operation independently of the carriage return.

30 20. In a typewriting machine, a carriage, a carriage return device having a connection to a source of fluid under pressure, a line spacing mechanism, an actuator for said line spacing mechanism having a connection branched from said first named fluid connection, a valve in said first named connection between the source of pressure and the branch to the line spacer, key controlled means for operating said valve whereby the carriage return and line spacing mechanisms may be operated together, a shunt connection from a point of said first connection between said valve and the source of fluid to a point of said branch to the line spacer beyond said valve, a second valve at the juncture of said shunt and said line spacer branch whereby said branch may be closed either to the shunt, or to the fluid supply except by way of the shunt, according to the setting of said second valve.

35 21. In a typewriting machine, a carriage, a carriage return device having a connection to a source of fluid under pressure, a line spacing mechanism, an actuator for said line spacing mechanism having a connection branched from said first named fluid connection, a valve in said first named connection between the source of pressure and the branch to the line spacer, key controlled means for operating said valve whereby the carriage return and line spacing mechanisms may be operated together, a shunt connection from a point of said first connection between said valve and the source of fluid to a point of said branch to the line spacer beyond said valve, a second valve at the juncture of said shunt and said line spacer

40 105 110 115 120 125 130

branch whereby said branch may be closed either to the shunt or to the fluid supply except by way of the shunt, according to the setting of said second valve, and key controlled means for opening and closing the passage through the shunt so that when the second valve is set for operation of the line spacer by way of the shunt, said key controlled means determines that operation independently of the carriage return, said first

means for operating said valve whereby the

and second key controlled means being operable together, so that, even though said second valve is set for independent operation of the carriage return and line spacer, the two mechanisms may be operated together by conjoint operation of the two key controlling means.

22. In a typewriting machine, the combination with a main fluid connection for returning the carriage, of a valve controlling said main connection, a branch of said connection controlled by said valve for line-spacing the platen in said carriage, a valve for shutting off said branch from said main connection, and a shunt comprising a valve for independently line-spacing said platen.

23. In a typewriting machine, the combination with a traveling carriage and a platen therein, of a key-operated means for simultaneously connecting said carriage to a source of power to return it and to line-space said platen, and means for simultaneously operating said carriage and platen by the operation of two keys.

24. In a typewriting machine, the combination with a traveling carriage and a platen therein, of power means for returning said carriage, a brake for retarding said carriage, means for modifying said power, and a single key for connecting said power to said carriage, for operating said brake and for modifying said power.

25. In a typewriting machine, the combination with a traveling carriage and a platen, of a source of fluid pressure for operating said carriage and platen, three keys for controlling said fluid pressure, and two valves controlled by said keys.

26. In a typewriting machine, the combination with a traveling carriage and a rod fast thereon, of a brake arranged to seize said rod, a fluid power mechanism to drive the carriage, and a key connected to operate

the brake and controlling the supply of power to the carriage.

27. In a typewriting machine, the combination with a traveling carriage, of a source of fluid pressure for operating said carriage, a valve for cutting off said fluid pressure, and a separate valve for modifying said pressure.

28. In a typewriting machine, the combination with a traveling carriage, of a source of power for moving said carriage, a key for varying the power, a brake, and means for operating said brake from said key.

29. In a typewriting machine, the combination with a traveling carriage, of power means for moving said carriage, a line-space mechanism for operating said carriage, power means for operating said line-space mechanism, a key for moving said carriage and operating said line-space mechanism by said source of power, and means controlled by said key for varying the power means for moving said carriage without varying it as applied to said line-space mechanism.

30. In a typewriting machine, the combination with a traveling carriage and a line-space mechanism, power means for operating said mechanism and moving said carriage, a brake for said carriage, and a single key for connecting said power means to said carriage and mechanism and for operating said brake.

31. The combination with a traveling carriage, of power means for returning it, a brake for said carriage, a key arranged to be depressed to cause said means to return said carriage, and means for operating said brake by rocking said key.
